UNITED STATES PATENT OFFICE.

SAMUEL COHN, OF NEW YORK, N. Y., ASSIGNOR TO MACHINE MANTLE SEWING COMPANY, OF NEW YORK, N. Y., A CORPORATION OF NEW YORK.

CENTER JAW FOR MANTLE-SEWING MACHINES.

No. 918,735.

Specification of Letters Patent. Patented April 20, 1909.

Application filed May 1, 1908. Serial No. 430,274.

To all whom it may concern:

Be it known that I, SAMUEL COHN, a citizen of the United States, and a resident of the city, county, and State of New York, have invented a new and useful Improvement in Center Jaws for Mantle-Sewing Machines, of which the following is a specification.

The object of my invention is to provide what is known as a wire jaw in which it will be practically impossible to entangle the mantle when it is placed on this jaw regardless of the rapidity with which it may be placed and also to hold the mantle properly while in the machine. This object is accomplished by my invention, one embodiment of which is hereinafter disclosed.

For a more particular description of my invention reference is to be had to the accompanying drawings forming a part hereof in which,

Figure 1 is a plan view of my improved jaw. Fig. 2 is a sectional view taken on the line 2—2 of Fig. 1, looking in the direction of the arrows.

Throughout the various views of the drawing similar reference characters designate similar parts.

My improved jaw 1 is provided with a base 30 2 composed of the two bars 3 and 4, the bar 4 being the upper bar. This bar is slotted to receive the upwardly extending jaws or fingers 5, which are preferably made of wire, and have their upper ends bent inward so 35 that they converge and are separated at the top by a space which is substantially the same as the diameter of the wire of which they are composed. Seven of these wire jaws or fingers 5 are shown, but it is obvious 40 that any number may be employed.

Immediately below these jaws or fingers 5 and fixed in the same planes therewith are the stops 6 which are preferably formed of wire and bent as shown in Fig. 2. These stops 45 6 are made round in cross section except where passing through recesses in the plates 3 and 4 so that these stops will not turn or shift their position in said recesses whereby each stop is fixed in its recess.

50 A guard 7 is bent so as to have its ends fixed in the plate 4 and throughout the

greater portion of its length it is substantially parallel with this plate 4 and above the openings between the ends of the jaws or fingers 5 and separated therefrom any suitable distance but preferably about as shown in Fig. 2. The upper ends of the extreme jaws or fingers are converged toward the other jaws or fingers as shown at 8 so as to bring these jaws or fingers well under the guard 7 at their upper extremities. The plates 3 and 4 may be held together by any substantial means, but are preferably united by screws, as indicated in dotted lines.

In view of the foregoing, the operation of my improved center jaw will be readily understood. Assuming it to be mounted in any suitable machine, such as that shown in my Patent No. 678,542, granted July 16th, 1901. The mantle is placed so that the opening at the lower end of the webbing is over the guard 7. As this mantle is lowered over the center fingers 5 which have their upper ends under this guard 7, they enter the interior of the webbing without engaging the same thereby avoiding all delays incident to the improper engagement of the webbing by the fingers or jaws 5.

While I have described and shown only one embodiment of my invention, it is obvious that it may be embodied in various forms all of which come within the scope of the annexed claim.

What I claim is:

A center jaw for mantle sewing machines, comprising a base, bent wire fingers having their central portions passing through said base, said fingers extending upwardly and having their upper ends converging so as to leave a space between said ends substantially equal to the diameter of said fingers, and a guard, made of a single piece of wire, secured in said base and having its upper side substantially parallel to said base and located over the openings between the ends of the fingers, substantially as described.

Signed at New York city—New York this 29th day of April, 1908.

SAMUEL COHN.
